CLAIM

I claim the ornamental design for a book prop, as shown and described.

DESCRIPTION

FIG. 1 is a perspective view of the book prop showing my new design.

FIG. 2 is a top plan view thereof.

FIG. 3 is a bottom plan view thereof.

FIG. 4 is a right side view thereof, the left side plan view being a mirror image.

FIG. 5 is a front side view thereof; and,

FIG. 6 is a back side plan view thereof.

The broken lines in FIGS. 1-6 illustrate the portions of the book prop that form no part of the claimed design.

1 Claim, 6 Drawing Sheets
